FRANK O. HOAGLAND, OF BRIDGEPORT, CONNECTICUT, ASSIGNOR TO THE UNION METALLIC CARTRIDGE COMPANY, OF BRIDGEPORT, CONNECTICUT, A CORPORATION OF CONNECTICUT.

TUBULAR CARRIER.

1,025,525.

Specification of Letters Patent.

Patented May 7, 1912.

Application filed February 28, 1912. Serial No. 680,558.

To all whom it may concern:

Be it known that I, FRANK O. HOAGLAND, a citizen of the United States, residing at Bridgeport, county of Fairfield, State of Connecticut, have invented an Improvement in Tubular Carriers, of which the following is a specification.

This invention relates to the class of tubular carriers illustrated and described in patent to Drake, Number 869,484, dated October 29, 1907, and has for its object to simplify and cheapen their construction and to greatly improve their operation in use. This I accomplish by dispensing with the use of plugs and forming the closures at both ends of the body from the material of the body itself. I thus avoid the use of separate parts and provide an absolutely safe and effective closure at each end of the body which cannot be opened or displaced by the contents in handling or transportation and which cannot be opened except in the regular way.

With these and other objects in view, I have devised the novel tubular carrier of which the following description in connection with the accompanying drawing is a specification, reference characters being used to indicate the several parts.

Figure 1 is an end view of the carrier with the closing piece in the closing position. Fig. 2, an elevation corresponding therewith. Fig. 3, a section on the line 3—3 in Figs. 1 and 5. Fig. 4, an end view illustrating a slightly variant form. Fig. 5, an elevation corresponding therewith. Fig. 6, a view illustrating the mode of opening the carrier; and Fig. 7 is a similar view showing the carrier opened for filling or for the removal of its contents.

10 denotes the body which is a tube of paper or other suitable material made sufficiently heavy to give the necessary strength and rigidity for carriers of the required length.

In the present instance, I have illustrated the device in use as a cartridge carrier or holder. The cartridges are placed in the carrier with the bullet ends forward. For convenience in description I will refer to the loading end of the carrier as the base and the other end as the tip. Near the tip of the body, I make one or more indentations 12 in circular arrangement. These indentations permit the body of the first cartridge

to pass freely but are engaged by its head, as clearly shown in Fig. 5, and prevent the cartridge from passing out. The indentations are shown as placed far enough from the end of the body to leave the bullet end 60 of the first cartridge effectually protected, as in Fig. 5.

The base of the tube is closed by, what I term, a closing piece, indicated by 13, which is a strip of the material of the body itself. 65 This closing piece may be formed as in Figs. 1, 2, 6 and 7, by making a single cross cut in the body at a short distance from the end leaving both ends of the closing piece attached and springing the closing piece, 70 i. e., the material of the body between the cross cut and the end inward as in Figs. 1 and 2. This construction enables me to shorten the body to the minimum and provides a perfectly safe closure which will 75 securely retain the cartridges in the body, is not detachable, will not open in use and will last as long as the body. It will be noted that the closing piece is an arc corresponding with the curvature of the body. The material of the body is sufficiently resilient so that the closing piece must remain in either the open or closed position; this for the reason that the closing piece is longer than the chord of the arc and must be pushed 80 past a line corresponding with the chord of the arc in either opening or closing. It should be noted that the construction is such as to reduce the length of the body to the minimum, thus effecting a saving in the 85 cost of stock.

If preferred, the bodies may be made slightly longer, as in Figs. 4 and 5, and the closing piece may be formed by making two cross cuts, instead of by making a single 95 cross cut near the end as in the other form.

In use, the closing of a carrier is effected by springing the closing piece inward from the position shown in Fig. 7 to that shown in the other views. It will be noted that the closing piece in this position effectually bars the escape of cartridges from the body. To open, it is simply required to take any convenient implement, as a lead pencil, and spring the closing piece outward which will leave the passage unobstructed as in Fig. 7. To close a tube after removing cartridges or refilling, the closing piece is simply pressed inward to the closing position, which can be readily done with the finger 110.

without any implement whatever. The resiliency of the material of the tube will then cause the closing piece to remain in the closing position until it is pressed outward 5 again to open, as in Fig. 6.

Having thus described my invention, I claim:

1. A carrier of the character described comprising a tubular body having near one 10 end an indentation adapted to be engaged by the contents and at the other end a closing piece consisting of a strip of the material of the body attached at the ends only and adapted to be sprung into and out of 15 the closing position.
2. A carrier of the character described comprising a tubular body, means for preventing the escape of the contents at the tip of the body and a closing piece at the 20 other end consisting of a strip of the material of the body attached at the ends only and adapted to be sprung into and out of the closing position.
3. A carrier of the character described 25 comprising a tubular body having near its

tip an indentation adapted to be engaged by the head of a cartridge, said body extending beyond the indentation to protect the bullet end of the cartridge.

4. A carrier of the character described 30 comprising a tubular body having at one end a closing piece consisting of a strip of the material of the body attached at the ends only and adapted to be sprung into and out of 35 the closing position.

5. A carrier of the character described, comprising a tubular body having near one end an indentation adapted to be engaged by the contents and at the other end a closing piece formed by making a cross cut in 40 the body leaving a strip, attached at the ends only, which may be sprung into and out of the closing position.

In testimony whereof I affix my signature in presence of two witnesses.

FRANK O. HOAGLAND.
